UNITED STATES PATENT OFFICE.

CALVIN D. DUNBAR, OF BUCKEYE, TEXAS.

LAMP EXTINGUISHER.

Application filed July 8, 1926. Serial No. 121,204.

This invention relates to improvements in lamp extinguishers, and it consists of the constructions, combinations and arrangements herein described and claimed.

5 An object of the invention is to provide a simple and inexpensive yet thoroughly efficient device for manually extinguishing the flame of kerosene and similar lamps, the device also being capable of automatic operation in some instances, when for example, the lamp accidentally falls.

10 Other objects and advantages will appear in the following specification, reference being had to the accompanying drawing, in 15 which

Figure 1 is a perspective view of a lamp burner with the improved extinguishing device applied,

20 Figure 2 is a detail cross section taken substantially on the line 2—2 of Figure 1. The burner shown in the drawing is of the type familiarly known as being used in connection with kerosene lamps although it may conceivably be another type of burner. 25 The burner comprises the base 1, the dome 2 which is suitably hinged at 3 upon the base to permit swinging back, and the wick tube 4 in respect to which the extinguishing device operates.

30 This device is composed of a shutter plate 5 and a weighted shutter 6. The weight 7 of the latter shutter may be composed of lead or other suitable substance, the mode of application of the weighting substance to the 35 shutter 6 being such that there is formed a recess 8 which fits over and contains the exposed end of the wick W when the shutters are in the extinguishing position (Fig. 2). To this end the shutter 6 has walls 9 (Fig. 40 1) which not only completes the recess mentioned but also provides places at which the supporting arms 10 are conveniently attached in a permanent manner.

The supporting arms 10 are bent at 45 to provide coaxial portions which are held upon the base 1 by clips 12 in such a manner as to constitute bearings. The supports are then bent again to form a central U-shaped tongue 13 beneath which the finger 14 of the 50 actuating lever 15 extends for the purpose of swinging the shutter 6 upon its pivots or bearings in order to lift it to the extinguishing position.

Branching fingers 16 of the lever 15 provide the support for the lever. To this end 55 the extremities of the branching fingers are

bent outwardly at 17 and introduced in holes 18 formed in a conveniently raised part of the base 1. The lever 15 terminates in a flat button 19, which the operator may depress 60 to actuate the extinguishing device.

A pair of supporting arms 20 carry the shutter plate 5. These are pivoted upon the base as at 21. The ends of the arms 20 are bent over in curved formation against one side of the plate 5 (Fig. 1) where they are gripped at two places by portions of the plate bent over thereupon as at 22 and 23. The plate 5 also has a central lip 24 which comes directly over the tongue 13, the same 70 action that swings the shutter 6 over to the closing position also swinging the shutter 5 upward upon its pivot into position to meet the shutter 6 and form a closure over the wick W. The plate 5, in meeting the 75 edge of the shutter 6, completes the foregoing recess, forming a chamber around the wick and extinguishing the flame.

The operation is readily understood. The shutters 5 and 6 normally assume the separated or open position in Figure 1. The shutters 5 and 6 and the actuating lever 15 are independent of each other, each being movable upon its own pivot. But the weight 7 of the shutter 6 has a controlling effect 80 upon each of the elements.

In gravitating to the foregoing open or separated position the shutter 6 necessarily carries the tongue 13 downward until the latter rests upon the base 1. The weight 7 is sufficiently heavy to overcome the lever 15, the tongue 13 therefore bearing down upon the finger 14 and holding the lever 15 with its button 19 in the elevated position. The shutter 5, in turn, rests upon the tongue 90 13 and thus gravitates to the open position also. If the operator were to lift the weight 7 independently of the lever 15, the weight of the free end of the lever would predominate over the weight of the shutter 5, and thus move the latter to the closed position. However, this is not done in practice and the weight 7 therefore insures holding both shutters open and the lever 15 in the elevated 95 position.

Should it be desired to extinguish the flame, the user presses down upon the button 19 whereupon the lever 15 rocks upon its pivots 17. The finger 14 is raised beneath the tongue 13, causing the supporting arms 10 to swing upon their pivots 12 and simultaneously cause the shutter 5 to swing upon 110

its pivot 21. Both shutters are thus carried upwardly (Fig. 2)) until they assume a closed position over the wick W. The recess 8 in the shutter 6, together with the shutter plate 5, forms a chamber in which the flame is snuffed out.

The foregoing description may be supplemented by a statement of the advantages of the invention. Although kerosene lamps have been widely displaced by more modern means of illumination, it is nevertheless the fact that they are still used to a large extent, principally in rural communities. Churches, meeting houses and residences are the frequent scenes of use of kerosene lamps. These are often held in brackets on the wall, and inasmuch as they are quite out of reach for the extinguishing of the flame by the more or less common method of blowing down into the chimney, it becomes convenient to provide the lever 15 which the operator may use by simply reaching up. It is deemed an obvious expedient to attach a chain to the lever 15 so that the lamp may be reached in case it is mounted exceptionally high.

While the construction and arrangement of the improved lamp extinguisher is that of a generally preferred form, obviously, modifications and changes may be made without departing from the spirit of the invention or the scope of the claims.

I claim:—

1. A lamp extinguisher comprising a base and a wick tube, a pair of shutters, means by which they are pivotally mounted upon the base beside the wick tube, actuating means mounted upon the base operatively engaged with one of the shutters to move it upon its pivot, and means on the other shutter engaged with a part of the first shutter so that both shutters move upon their pivots simultaneously to the closing position over the wick tube.

2. A lamp extinguisher comprising a base and a wick tube, a pair of shutters, means by which the shutters are pivotally mounted upon the base at opposite sides of the wick tube, a tongue incorporated in one of the

shutters, a lip incorporated in the other bearing on the tongue, and actuating means pivoted upon the base having a finger engaging the tongue for simultaneously moving both shutters to the closing position upon operation of the actuating means.

3. A lamp extinguisher comprising a base and a wick tube, a pair of shutters, supporting arms for each of the shutters, means upon the base by which portions of the arms are pivotally mounted, a tongue incorporated in the pivotal mounting of the supporting arms of one of the shutters, a lip carried by the other shutter being in engagement with the tongue, and an actuating lever pivotally mounted upon the base having a finger engaging the tongue for lifting the tongue and lip simultaneously to move the shutters to a closing position over the wick tube.

4. A lamp extinguisher comprising a base and a wick tube, an actuating lever pivoted upon the base having a finger at one end and a button at the other, a shutter plate pivotally mounted upon the base and having a lip situated over the finger, and a weighted shutter pivotally mounted upon the base having a tongue disposed between the finger and lip, said weighted shutter depressing the finger by means of the tongue to keep the button in elevated position, said lip gravitating to a resting position upon said tongue.

5. In combination with the base and wick tube of a burner, a pair of supporting arms pivotally mounted upon the base extending to sides of the wick tube opposite to the pivots thereof, shutters affixed to the ends of the pairs of supporting arms, one of the shutters being weighted, the other consisting of a plate having bent over portions gripping the ends of the respective supporting arms, a lip on the latter shutter, a tongue formed on the supporting arms of the former shutter, an actuating lever having branching fingers pivotally mounted upon the base, and a finger extending beyond said branching fingers into engagement with the tongues for the purposes described.

CALVIN D. DUNBAR.
